UNITED STATES PATENT OFFICE.

ELMER S. SMITH, OF BOUND BROOK, NEW JERSEY, ASSIGNOR, BY MESNE ASSIGNMENTS, TO INTERNATIONAL ACCESSORIES MANUFACTURING COMPANY, OF WILMINGTON, DELAWARE, A CORPORATION OF DELAWARE.

CARBURETER.

1,184,267.

Specification of Letters Patent. Patented May 23, 1916.

Application filed May 12, 1911. Serial No. 626,678.

To all whom it may concern:

Be it known that I, ELMER S. SMITH, a citizen of the United States, and a resident of Boundbrook, Somerset county, State of New Jersey, have invented certain new and useful Improvements in Carbureters for Hydrocarbon-Engines, of which the following is a full and clear specification illustrated in the accompanying drawings, the particular novel features being more fully pointed out in the annexed claims.

The object of my invention is to provide a simple and highly efficient carbureter for automatically atomizing liquid fuel and mixing it with air to form a mixture of the requisite quality in accordance with the amount of work which the engine is to perform at the time, to which the carbureter is attached.

20 My improved carbureter is adapted for use in stationary hydrocarbon engines as well as in hydrocarbon engines used for propelling vehicles or boats or the like.

The quantity and quality of gas supplied 25 to the cylinders of a hydrocarbon engine should vary in accordance with the demands made on the engine and the quantity of the fuel, for instance gasoline, supplied to the air on the suction strokes of the piston or 30 pistons, should be capable of automatic regulation as well as of predetermined adjustment and to accomplish these objects are among the purposes of my invention.

In particular my invention relates to improvements on the carbureter described and 35 illustrated in my copending application, Serial Number 497,646, filed May 22nd, 1909, of which the structure illustrated in the present application is an improvement in 40 form as well as in function.

In the accompanying drawings: Figure 1 is a side elevation of my improved carbureter, the carbureter being shown in full view. Fig. 2 is a vertical section on the line 45 $x-x$ in Fig. 1 seen in the direction of the arrow. Fig. 3 is a vertical section through the carbureter at right angles to the section shown in Fig. 2. Fig. 4 is a full view of the float receptacle illustrated in vertical 50 section in Fig. 3. Fig. 5 is a sectional end view of the trunnion 25 on the line $g-g$, in the direction of the arrow. Fig. 6 is a plan view of a small portion of the right hand portion of the carbureter shown in Fig. 1,

the section shown in Fig. 6 being taken on 55 the line $y-y$ in Fig. 1. Fig. 7 is a longitudinal section in larger scale of one of the fuel nozzles attached to the float receptacle. Fig. 8 is a plan view of the lower hemisphere of the carbureter with the float receptacle in it. Fig. 9 is an inside view of the upper hemisphere of the carbureter shown in Fig. 1 with the float chamber removed. Fig. 10 is a section through the outer shell of the carbureter on the line $x-x$ in Fig. 1, 60 the float receptacle being shown in full view and tilted into its extreme position at which no fuel is supplied to the engine. Fig. 11 is a similar view to that shown in Fig. 10 with the lower hemisphere of the shell removed 65 and the float receptacle tilted into the opposite extreme position at which the maximum amount of gas is supplied to the engine. Fig. 12 is a full side elevation of a modification of the form of carbureter illustrated in 70 Fig. 1, and Fig. 13 is a vertical section through the carbureter shown in Fig. 12, on the line $z-z$ seen in the direction of the arrow.

The fundamental idea of my carbureter as 75 disclosed in the aforesaid copending application is the use of a fuel receptacle pivotally mounted inside of an air intake casing leading to the engine, the fuel receptacle being provided with a plurality of fuel nozzles 80 mounted at different levels above the normal gasoline level in the receptacle, so that when 85 said receptacle is tilted on its pivots a larger or smaller number of fuel nozzles are carried into a position in which gasoline will 90 flow out of them, so that the air passing through the intake pipe may be enriched with fuel from such nozzles. This same idea has been reduced to practice in the 95 present application in my improved form in the following manner.

Referring to Figs. 1 and 2, 10 and 11 represent together a shell or casing, the base of which forms an air inlet while the threaded upper end 12 forms the mixture outlet, 100 whereby the casing may be attached to the air intake pipe of the engine. These two portions have approximately the form of two hemispheres as may be seen from these two figures and they will hereinafter be referred to as such. The upper hemisphere 10 is a hollow casting, its interior forming the carbureting chamber, and the lower hemisphere 105

consists of a ring 13 having its upper face of substantially the same diameter as the diameter of the upper hemisphere and flaring outwardly as shown in Figs. 1 and 2, a 5 substantially hemispherical screen cap 14 being attached to the inside of the larger end of this ring so that the ring and cap together form the lower hemisphere of the carbureter. The screen cap is made of wire 10 netting, preferably brass wire. The two hemispheres may be joined by any suitable means for instance as shown in Figs. 1 and 2, where two lugs 15, 15 and 16, 16 are provided on diametrically opposite sides of 15 each hemisphere, respectively, the lugs 15 and 16 of each side being yieldingly held together by means of a spring hasp consisting of a bolt 17 having a half round head 18 at its lower end with which it rests in a 20 socket provided in lug 16. The bolt passes through lugs 16 and 15, and its outer end protruding beyond lug 15 is disposed in a thimble 19 with a spring 21 interposed between a nut 20, attached to the upper 25 bolt end, and the bottom of the thimble. Thimble 19 is curved at its lower end with which it is seated in lug 15. Thus the two hemispheres are held yieldingly together. One of the lugs 15, for instance the 30 one on the right hand side in Fig. 2, is slotted as shown at 22 (in Fig. 9 on the left hand side) so that by pulling the thimble 19 from its seat the hasp may be swung out and thus the two lugs be disconnected from each 35 other, whereas if desired lug 15 on the left hand side may not be provided with such slot, so that the lower hemisphere is prevented from being disconnected entirely from the upper hemisphere. However, by providing the 40 cone shaped portions 28 on all the lugs where indicated, it is possible to swing the lower hemisphere off the upper as if hinged together and at the same time turning them away from each other so that the inside of 45 each hemisphere is made accessible thereby.

Referring now to Figs. 2 and 3. Within this outer shell of the carbureter formed by the two hemispheres is disposed on horizontal trunnions 24 and 25 float receptacle 26, 50 which consists of an upper half 27 which carries trunnions 24 and 25, as clearly seen in Fig. 4, and a lower half 28. The lower half is attached to the upper half by means of a central rod 29 as shown in Figs. 2 and 55 3. This rod has a shoulder 30 bearing against the recessed portion 31 of the upper half while its lower end is screwed into a boss 32 provided in the lower half, so that by turning nut 33, the two halves may be 60 clamped tight together. The trunnion axis $a-a$ coincides with the plane at which the hemispheres 10 and 11 of the outer shell join, and both hemispheres are correspondingly provided with trunnion bearings 34, 35, for the upper hemisphere

and 36, 36 for the lower hemisphere. Both trunnions are hollow as shown in Fig. 3 but closed at their outer ends, trunnion 24 having a rocking arm 37 attached to it which protrudes through trunnion bearing 35 70 which for this purpose has a cut away portion 38 as shown in Fig. 9, which permits the rocking of the float receptacle by means of arm 37 on its trunnion bearings through a certain angle. Trunnion 25 is preferably 75 closed by means of a screw plug 39 as shown in Fig. 3. Within the latter trunnion is mounted a sleeve 40, held in place therein by means of screw 41, and in this sleeve is disposed a transverse pivot pin 42, which runs through this sleeve at an angle to the horizontal plane through the trunnion axis $a-a$ and which is also disposed slightly above this axis. The location of this pin may be clearly seen from Fig. 5 which 80 shows an end view of trunnion 25 on the section line $g-g$ in Fig. 4. The pivot pin 42 is shown in this figure in dotted lines. On pivot pin 42 is mounted a lever 43 which carries on its inner end which is located in float receptacle 26, the float 44, this float having an annular shape so as to permit the passage of rod 29, previously mentioned, through its center without interfering with the movement of the float. The other lever 95 end 45 protrudes into the hollow space within trunnion 25 and carries at its outer end a knob 46 preferably in the form of a rounded roller journaled on said lever to lessen friction and wear, which is in line with an 100 opening 47 provided in the cylindrical wall of trunnion 25 at its upper side as shown in Figs. 3, 4 and 5. In particular from Fig. 5, it will be noted that this opening occupies part of the circumference of the trunnion 105 wall, so as to permit the free passage of float valve 48 through it, the lower end of which rests upon the outer periphery of knob 46. Float valve 48 is housed in valve receptacle 49 of the form commonly known 110 in the art, its cone 50 seating in the receptacle at 51, and the gasolene being supplied through the lateral outlet 52 of the receptacle.

The valve stem is three-cornered as 115 shown in Fig. 6 so as to permit the free flow of gasolene between it and the walls of the receptacle as is also commonly known in the art. Float receptacle 29 is seated with its lower end 53 in a hollow boss 54 120 integral with the upper hemisphere 10 and in vertical alinement with the trunnion axis $a-a$. The lower end 53 of the valve receptacle is square as shown in Fig. 6, only substantially its corners touching the round 125 boring of boss 54. The openings produced thereby between the square and the boss wall have the purpose of admitting air to the interior of the boss of the float receptacle for the purpose which will be hereinaf- 130

ter referred to. For this reason the valve receptacle does not seat tightly on the upper end of boss 54 the small shoulder preventing its seating so that air may be admitted to the interior of trunnion 25. Set screw 55, Fig. 6, holds the valve receptacle in place in the boss. The gasoline level is supposed to be in line with the trunnion axis $a-a$, Fig. 3, and the float is adjusted accordingly so that at this level the float 44 assumes substantially the position as shown in Fig. 3. In this position the gasoline valve 50 is seated by its own weight as well as by the gasoline pressure in the line, whereby its lower end just touches the periphery of knob 46 laterally of the vertical line through the center of the knob as shown in Fig. 5. When the gasoline level falls the float following raises knob 46, which in turn lifts valve 50 from its seat and admits gasoline whereby the level is raised again to the normal at which valve 50 is seated again. As previously mentioned the foot of valve 48 touches knob 46 at a point laterally of the vertical line through the center of the knob. If now for instance the float receptacle is rocked by means of its arm, previously described with reference to Fig. 5, which causes trunnion 25 to revolve counterclockwise, it will be noted that during such motion the knob, owing to pivot pin 42 being mounted eccentrically to the trunnion axis, will be raised slightly so that valve 50 is lifted thereby slightly from its seat and admits gasoline. This, however, occurs only at the rocking of the float receptacle through a considerable angle into a position at which the maximum amount of gasoline is required and a higher gasoline level is preferable, as will be hereinafter described in detail.

As will be noted from Figs. 2 and 4, the upper receptacle portion 27 is provided at one side with a number of nozzles, outlets or orifices 60 distributed over one half of the upper portion in staggered relation commencing with one nozzle slightly below the gasoline level, when the float receptacle is in such position that its operating arm stands vertical. The other nozzles are located above at various distances from the lowermost nozzle, as clearly shown in Fig. 4. In Fig. 2, the lowermost nozzle 60 is shown with the float receptacle in the position at which the nozzle is slightly below the gasoline level $l-l$, two other nozzles being shown disposed at various distances from this level. It will be noted that if in Fig. 2, the float receptacle is tilted clockwise at its trunnions, one or more of the gasoline nozzles located above the lowest nozzle, will be immersed into the gasoline and deliver gasoline through the orifice 61, Fig. 7, to the outside. On the other hand, if the float receptacle is tilted from the position shown in Fig. 2, counterclockwise even the lowermost nozzle will emerge from the gasoline and no gasoline can be delivered to the outside through any of these nozzles. The latter position is shown in Fig. 10, and the former position in Fig. 11, with the gasoline level marked $l-l$.

From Figs. 2 and 4, it will be noted that the upper half 27 of the float receptacle is provided with a circular flange 62, which is substantially of the same diameter as the inner rim 63 of the upper hemisphere 10 of the carbureter shell, so that when the float receptacle is in the position shown for instance in Fig. 2, it will obstruct the passage of air from the outside through screen 14, into the space between the upper hemisphere and the float receptacle which leads to the engine save for a small space at which this rim is cut away. This space may be seen in front view in Fig. 4, between the points $b-b$ and in plan view in Fig. 8, where also the rim 63 may be seen in plan view. At this cut away portion the lowermost nozzles 60 are provided so that if the air is drawn in by the engine in entering the carbureter through screen 14, it can only pass upwardly through the cut away portion $b-b$ which leads it past the nozzles so that it is enriched with gasoline at this point, so long as the receptacle is not tilted. However, when the receptacle is tilted clockwise more or less into the position shown in Fig. 11, flange 62 receding downwardly from rim 63 at the right hand side of the figure, enlarges the passage between the lower and upper hemisphere, thus admitting more air which then rushes past a greater or smaller number of nozzles which are brought by such tilting into a position in which they can deliver gasoline from the float receptacle to the outside in the manner previously described. It will be noted that thus with the greater admission of air also the amount of fuel supplied to the air is increased, and by properly dimensioning the size of the orifices of nozzles 60 and their location and number, it may easily be brought about that no matter how little or how much the float receptacle is tilted, or in other words, how much or how little gas is admitted to the engine, it will always have the same quality; or it may be brought about that according to the amount of fuel required by the engine at a certain time, a certain quantity of gasoline can be admitted for a certain amount of air admitted to the engine. Thus the mixture may be made richer or poorer for any desired throttle position. It will also be noted from Fig. 11, that when the float receptacle is tilted into a position in which the nozzles supply fuel and in which air is allowed to pass from the lower to the upper hemisphere, this can occur only at the right hand side of the float receptacle, 120 125 130

respectively at the right hand side of the upper hemisphere, whereas at the left hand side of the hemisphere rim 62 of the float receptacle still forms a substantial obstruction to the air save for a very small space, owing to the spherical shape of the wall of hemisphere 10.

The passage of air from the space between the nozzles and the wall of the upper hemisphere to the upper opening 12, however, is not entirely unobstructed, a valve 65 being attached to the upper portion 27 of the float receptacle in such manner that it seats against a valve seat 66 which is formed spherical and concentric with the receptacle, the valve being held onto its seats by means of spring 67. This structure can be clearly seen from Figs. 2, 3, 4, 10 and 11. The valve is mounted on an upper extension of rod 29 so that it can slide on this rod and spring 67 is placed into recess 31 of the float receptacle previously referred to. From the drawings it will be obvious that the arrangement is such that the valve may be depressed downwardly into this recess 31, when it is lifted from its seat by the following means. Extending in the direction of the plane in which the float receptacle is tilted a rib is provided on the upper side of valve 65 which may be plainly seen at 68 in cross section in Fig. 2, and in side view in Figs. 10 and 11 and in front view in Fig. 4. This rib or cam is curved, not with the same radius from the trunnion axis to the valve seat, but it increases in height from the seat portion of the valve toward the valve center as may be clearly seen from Figs. 2, 10 and 11. Thus if the float receptacle is tilted to the right as shown in Fig. 11, the valve not only opens the passage toward the mouth 12 of the carburetor by swinging away from its seat, but it also is depressed downwardly, and thus moved away from its seat by means of cam 68 which rides up onto valve seat 66 in the manner shown in Fig. 11. This increases the passageway to the upper portion of the carburetor and it is obvious that the form of this cam 68 may be chosen so that the valve may be lifted any suitable distance off its normal seat when the float receptacle is rocked into active position in which the air is enriched with fuel. On the other hand, if the float receptacle is rocked in the opposite direction as shown in Fig. 10, valve 65 merely opens the passageway from the lower portion of the upper hemisphere to the upper portion in similar manner in which farther below rim 62 admits pure air from the lower hemisphere to the upper hemisphere. Thus if for instance in case the hydrocarbon engine is used for a vehicle, and the latter should descend a hill, where no power is required from the engine, the float receptacle may be tilted into the position shown in Fig. 10,

wherein in the first instance no fuel is supplied from any of the nozzles and secondly a considerable amount of air may be admitted to the engine nevertheless, which will act as a brake as well as also to cool 70 the cylinders.

In the position in which the float receptacle 26 is shown, for instance in Fig. 2, only the lowermost nozzle 60 as previously described, is able to furnish gasoline to the 75 small amount of air which can pass upward through the cut away portion *b*, *b*. In this position of the float receptacle valve 65 is completely seated and no air could pass upward to the engine, were it not for a small 80 V-shaped cut provided at the left hand side of valve 65 at 69 in Fig. 2. This V-cut may be clearly seen in plan view in Fig. 8. When the receptacle is tilted into active position increases in size and thus admits air according to the degree to which air is admitted from the lower hemisphere to the upper hemisphere of the outer shell until the cam 68 previously described comes into action which lifts the valve from its seat. Besides 90 this V-shaped cut 69 there may be also a few holes provided in the web of the valve as for instance indicated at 70 in Figs. 2 and 8 which may thus determine the minimum amount of mixture which is admitted to the 95 engine, and which may be just sufficient to keep the engine running without load. It is of course obvious that the holes 70 may be omitted and V-cut 69 enlarged accordingly.

It is well known that in starting a hydrocarbon engine it is desirable quite frequently to supply an extra rich mixture for the first few strokes, which is generally known in the art as a socalled "priming charge." This charge is frequently supplied to the cylinders directly through socalled priming cocks; also recently carburetors have been fitted out with a butterfly-valve or similar means at the mouth of the air intake of the carburetor which, when closed, causes a 100 greater amount of gasoline to be drawn from the gasoline nozzles by the suction of the engine through the lack of air supply. To provide a richer mixture for the starting, I provide the following means. Substantially across the whole width of the cut away portion *b*, *b* in Fig. 4, is stretched a fine wire screen 80 which forms a pocket in front of the lowermost nozzle 60 as will be clearly seen from Fig 2. In order to start the engine the float receptacle 26 is put into the position shown in Fig. 2, in which the lowermost nozzle is slightly below the gasoline level as previously described. By the time the operator gets ready to crank up the 105 engine a quantity of gasoline has oozed out of this nozzle and spread over the fine screen 80 so that when the engine draws in mixture this finely divided fuel on screen 80 is atomized by the rush of air in addition to the 110 120 125 130

gasolene continuously furnished by the lowest nozzle 60 when the engine is running. This amount collected on screen 80 is sufficient to prime the engine. While the engine is running of course screen 80 remains completely dry. In order to avoid a vacuum being formed inside of float receptacle 26 above the gasolene, which would tend to affect the amount of fuel furnished by the nozzles, I provide a small vent opening 81 which communicates with the space in the upper hemisphere between valve 65 and rim 62 of the float so that through this opening, the pressure between these two spaces may easily be equalized. Besides it has been previously stated with reference to fuel valve receptacle 49 that the lower portion 53 of this receptacle is square so that as also previously stated there are small passages of air between the sides of the square and the round boring or boss 54, which lead from the outside to the interior of trunnion 25 and thus to the interior of the float receptacle 26. Thus when the carbureter is in operation and a vacuum should tend to form inside of the receptacle, air is also supplied through these last mentioned passages which are marked 85 in Fig. 6. This slight air supply to the interior of the float receptacle has also the advantage of preventing any leakage of gasolene to the outside which might be spilled onto the trunnion bearing when entering the interior of the trunnion through opening 47.

It may be stated with reference to the number of nozzles which may be attached to the float receptacle that for instance in case it should be found that in a certain position of tilting too many nozzles are supplying fuel one or the other according to their location, may be substituted by a nozzle with a small orifice, or with no orifice as shown at 60^a Fig. 4, and thus any suitable amount of gasolene may be supplied to the air for a given position of the float receptacle.

In Figs. 12 and 13, I have illustrated a modified form of the carbureter just described which pertains not so much to the operation of its essential elements as to the outer form of the lower hemisphere of the shell which surrounds the float receptacle. In Fig. 13 this form is shown in longitudinal section on the line z—z seen in the direction of the arrows in Fig. 12 and it will be noted that the upper hemisphere 19, so far as its shape and function are concerned, is the same as that shown in the modification previously described; also the construction of the float receptacle 20 and valve 65 is the same so that the description of these elements in the modified form may be omitted. The form of the lower hemisphere, however, is considerably distinguished from that of the carbureter shown in Figs. 1 to 11. In the

modification just described, it will be noted and it has also been mentioned that the annular portion 13 which joins the upper hemisphere 10 (as for instance clearly shown in Fig. 2) flares outwardly. This affords a very convenient unobstructed passage for the air drawn in through screen 14, inasmuch as there is an annular space of considerable width between the lower edge of rim 13 and the lower half of the float receptacle 26. In the form shown in Figs. 12 and 13, on the other hand, it will be noted that the rim 90 with which the lower hemisphere is joined to the upper hemisphere 10, is cylindrical, screen 14 being otherwise joined to the lower edge of the rim in similar manner as the screen 14 is joined to the rim in the form just described. This form may be convenient in certain instances where only small space is available for the carbureter. However, it will be noted that by forming rim 90 cylindrical the annular space between the rim and the lower portion of float receptacle 26, now becomes considerably smaller so that the air passage past the fuel nozzles is considerably obstructed thereby. In order to supply sufficient air in this case when the throttle is wide open and a large amount of air is required, I provide windows 91 in rim 90 opposite from where the fuel nozzles are located and I preferably provide these windows with wire screen so that through these windows air can be freely supplied to the interior of the carbureter. The other distinguishing feature of the form illustrated in Figs. 12 and 13 is the manner in which the lower hemisphere of the outer shell is joined to the upper.

In the modification shown in Figs. 1 to 11, and particularly as shown in Fig. 2, the two hemispheres are joined together by spring hasps 17—21. These spring hasps have the advantage of yieldingly drawing the lower hemisphere against the upper hemisphere whereby thus the trunnion bearings 34—36 are pressed tight against the trunnions and thus prevent leakage of the gasolene and also compensate for wear. These spring hasps also have the advantage that in case of socalled back firing of the engine through the carbureter which is likely to occur in case of too lean a mixture, the lower hemisphere will slightly yield owing to the construction of the spring hasps and prevent injury to the carbureter.

In the modification shown in Figs. 12 and 13 the two forms are joined together by means of a hinge 92 at one side and a spring clasp 93 at the opposite side which embraces the bead 94 provided at the rim of the upper hemisphere. To sufficiently and yieldingly press the trunnions of the float receptacle against the upper trunnion bearings, a spring 95 is provided in the wire basket 14

to which it is suitably attached at both ends. The boss 32 of float receptacle 26 into which rod 29 is screwed from the inside, protrudes to the outside correspondingly and spring 95 bears against this boss, the shape of spring 95 conforming with the circle which the boss describes when the float receptacle is tilted into and out of operative position.

10 I have found that when the carbureter is in action the inrushing air, acting against the underside of the fuel receptacle, tends to lift it and hold its trunnions firmly against their upper seats in the casing, thus sealing the joint effectually from leakage of fuel. When the carbureter is not in action, the fuel passage is closed by the valve, and the trunnions are as heretofore described continued to be held up by the springs.

15 I claim:

1. A carbureter of the character described, having a shell provided with an air inlet and a mixture outlet, a rotatable fuel receptacle disposed in said shell and having means for supplying fuel to and discharging it from said receptacle, a valve for controlling the supply of fuel to said receptacle and means within the receptacle for controlling said valve.

2. A carbureter of the character described, having a shell provided with an air inlet and a mixture outlet, a rotatable fuel receptacle disposed in said shell and adapted in normal position to act as a valve for the passage therethrough and having means for supplying fuel to and discharging it from said receptacle, a valve for controlling the supply of fuel to said receptacle and means within the receptacle for controlling said valve.

3. A carbureter of the character described, having a shell provided with an air inlet and a mixture outlet, an approximately spherical rotatable fuel receptacle disposed in said shell and having means for supplying fuel to and discharging it from said receptacle, a valve for controlling the supply of fuel to said receptacle, and means within the receptacle for controlling said valve.

4. A carbureter of the character described, having a shell provided with an air inlet and a mixture outlet, and between them an approximately hemispherical carbureting chamber, and a rotatable fuel receptacle disposed in said shell and adapted in normal position to act as a valve for the passage therethrough and having means for supplying fuel to and discharging it from said receptacle.

5. A carbureter of the character described, having a shell provided with an air inlet and a mixture outlet, a rotatable fuel receptacle disposed in said shell, and having means for supplying fuel to and discharg-

ing it from said receptacle, a valve for controlling the supply of fuel to said receptacle and means within the receptacle for controlling said valve, the said means pivoted to and rotatable with the receptacle.

6. A carbureter of the character described, having a shell provided with an air inlet and a mixture outlet, a rotatable fuel receptacle disposed in said shell and having means for supplying fuel to and discharging it from said receptacle, a valve for controlling the supply of fuel to said receptacle and means within the receptacle for controlling said valve, the connection between the said last mentioned means and the valve being such as to increase the fuel supply when the receptacle is rotated from normal.

7. A carbureter of the character described, having a shell provided with an air inlet and a mixture outlet, a rotatable fuel receptacle mounted in said shell and having a hollow trunnion, the wall of the receptacle being apertured to discharge fuel in increasing quantities as the receptacle is rotated from normal, valve-controlled means for supplying fuel to said receptacle through said hollow trunnion and a float within the receptacle operatively connected to the fuel supply valve.

8. A carbureter of the character described, having a shell provided with an air inlet and a mixture outlet, a rotatable fuel receptacle mounted in said shell and having a hollow trunnion, the wall of the receptacle being apertured to discharge fuel in increasing quantities as the receptacle is rotated from normal, valve-controlled means for supplying fuel to said receptacle through said hollow trunnion and a float within the receptacle operatively connected to the fuel supply valve, and means for varying the connection between the float and the valve to increase the fuel supply when the receptacle is rotated.

9. A carbureter of the character described, having a shell provided with an air inlet and a mixture outlet, a rotatable fuel receptacle mounted in said shell, the wall of the receptacle being apertured to discharge fuel in increasing quantities as the receptacle is rotated from normal, valve-controlled means for supplying fuel to said receptacle, and a float within the receptacle operatively connected to the fuel supply valve, means for varying the connection between the float and the valve to increase the fuel supply when the receptacle is rotated, and means for stopping the fuel supply when the receptacle is rotated in position to prevent discharge of fuel.

10. In a carbureter, the combination comprising a housing having an air inlet and a mixture outlet and whose diametrical horizontal cross sectional area is less than all other diametrical areas, a gasoline container

pivotally mounted in said housing and having a maximum external cross sectional area substantially co-extensive with the diametrical horizontal cross sectional area of said

- 5 housing, said container itself constituting a valve and being adapted when rotated to admit a graduated supply of air between its outer surface and the inner surface of said housing and the said container being 10 provided with one or more orifices extending through the walls of said container, adapted to permit the escape of gasoline from said container and into said housing.

11. A carbureter of the character described, having a substantially hemispherical shell open at diametrically opposite sides to afford an air passage therethrough, a rotatable fuel receptacle disposed therein having its horizontal dimensions, substantially 15 equal to the inner horizontal dimensions of said shell and having its pivotal axis coinciding with the plane of said horizontal dimension, but having a smaller vertical dimension so as to normally obstruct said passage and when rotated to gradually open said passage, said receptacle having an apertured wall for discharging fuel into said shell in amounts increasing with the angle of rotation whereby said passage simultaneously increases in size with said fuel amount.

12. A carbureter of the character described, having a substantially hemispherical shell open at diametrically opposite sides to afford an air passage therethrough, a rotatable fuel receptacle disposed therein having its horizontal dimensions substantially equal to the inner horizontal dimensions of said shell and having its pivotal axis coinciding with the plane of said horizontal dimension, but having a smaller vertical dimension so as to normally obstruct said passage, and when rotated to gradually open said passage, said receptacle having an apertured wall for discharging fuel into said shell in amounts increasing with the angle of rotation, whereby said passage simultaneously increases in size with said fuel amount, said receptacle having means for supplying fuel to it and means within its walls for controlling said fuel supply to maintain a constant fuel level therein.

13. In a carbureter, the combination comprising a housing, and a gasoline container of approximately spherical configuration pivotally mounted therein, said container being of sufficient size to approximately extend completely across the said housing at the point of maximum horizontal cross-sectional area of the container, and said container being provided with orifices adapted to admit of the passage of gasoline from the interior of said container to the interior of said housing in exact accordance with the requirements therefor.

14. In a carbureter, the combination com-

prising a housing permitting of access to its interior and having an air-inlet opening and a mixture outlet opening, readily removable means, including a gasoline container pivotally mounted in said housing intermediate said openings and adapted to seal communication therebetween when in a normal inoperative position, said container being provided with orifices which extend through the wall thereof, and means for optionally depressing or elevating said orifices with respect to the level of gasoline within said container whereby the gasoline may be fed from said container in accordance with the requirements of an engine, and means for temporarily connecting said container, while still permitting of rotation thereof, with a valve-controlled gasoline supply conduit adapted to cut off automatically the flow of gasoline therefrom upon the removal of said container from said housing and adapted to normally permit the flow of gasoline into said container when the gasoline therein falls below a predetermined level.

15. A carbureter having a chamber formed by an outer shell of substantially spherical shape divided into two halves which are suitably connected with each other, each half having an opening for the passage of mixture or air through said shell, said shell containing a float receptacle oscillatorily disposed therein on trunnions arranged on a substantially horizontal axis, and adapted to contain liquid fuel, means for supplying the fuel through one of said trunnions to said receptacle, a valve suitably connected with said float to maintain a constant fuel level in the receptacle, said receptacle having a plurality of fuel nozzles disposed in its wall and adapted to be rendered active in larger or smaller number according to the angle to which said receptacle is tilted to mix with the fuel air drawing through said chamber past said nozzles.

16. In a carbureter of the character described, having a substantially spherical shell formed of two joined halves, a float receptacle disposed therein adapted to oscillate on trunnions journaled in said shell, a float in said receptacle attached to an arm pivotally disposed in a sleeve fastened in one of said trunnions, said trunnion having an opening in the upper portion of its wall which communicates with a fuel valve chamber attached to the upper half of said shell permitting fuel to pass from the chamber into the receptacle, and also permitting the foot of a valve disposed in the chamber to protrude through said trunnion opening, said float having its supporting arm extending beyond its pivot, and having its free end in contact with said valve foot for operating it with the rise and fall of the float to maintain a constant fuel level in said receptacle.

17. In a carbureter of the character de-

- scribed, having an outer shell forming the carbureting chamber and a fuel receptacle rotatably disposed therein on trunnions and adapted to discharge fuel into said shell and 5 a valve housing detachably mounted on said shell and containing a valve for controlling the fuel supply to said receptacle through one of said trunnions, the interior of said receptacle communicating with the outside 10 air through a slight leakage provided at the joint between said valve housing and said shell.
18. In a carbureter, the combination with an outer shell having an air inlet and a 15 mixture outlet, a fuel receptacle rotatably disposed therein and dividing said shell into an air- and a mixture compartment and normally substantially closing the passage therebetween, means for rotating said receptacle to gradually open said passage, and means 20 in the receptacle wall for simultaneously supplying fuel into said mixture compartment in amounts increasing with the size of said passage, and a valve member disposed in said mixture outlet and operatively connected with said receptacle to close said outlet when the receptacle is in normal position and to open it in accordance with the rotation of said receptacle.
- 25 19. In a carbureter, the combination with an outer shell having an air inlet and a mixture outlet, a fuel receptacle rotatably disposed therein and dividing said shell into an air- and a mixture compartment and normally substantially closing the passage therebetween, means for rotating said receptacle to gradually open said passage, and means 30 in the receptacle wall for simultaneously supplying fuel into said mixture compartment in amounts increasing with the size of said passage, and a valve member disposed in said mixture outlet and operatively connected with said receptacle to close said outlet when the receptacle is in normal position and to open it in accordance with the rotation of said receptacle, said valve having an opening for admitting a fixed amount of mixture to said mixture outlet when the valve is closed.
- 35 20. In a carbureter, the combination with an outer shell having an air inlet, and a mixture outlet, a fuel receptacle rotatably disposed therein and dividing said shell into an air- and a mixture compartment, and normally substantially closing the passage therebetween, means for rotating said receptacle to gradually open said passage, and means 40 in the receptacle wall for simultaneously supplying fuel into said mixture compartment in amounts increasing with the size of said passage, and a valve member disposed in said mixture outlet and operatively connected with said receptacle to close said outlet when the receptacle is in normal position and to open it in accordance with the rotation of said receptacle, said valve having an opening for admitting a fixed amount of mixture to said mixture outlet when the valve is closed.
- 45 21. In a carbureter, the combination with an outer shell having an air inlet and a mixture outlet, a fuel receptacle rotatably disposed therein and dividing said shell into an air- and a mixture compartment and normally substantially closing the passage therebetween, means for rotating said receptacle to gradually open said passage, and means 50 in the receptacle wall for simultaneously supplying fuel into said mixture compartment in amounts increasing with the size of said passage, and a valve member disposed in said mixture outlet and operatively connected with said receptacle to slide off and onto its seat in accordance with the rotation of said receptacle when the latter is rotated out of and into normal position in either direction, said valve having an opening admitting a fixed amount of mixture to said outlet when the valve is closed and the receptacle is in normal position.
- 55 22. In a carbureter, the combination with an outer shell, having an air inlet and a mixture outlet, a fuel receptacle rotatably disposed therein and dividing said shell into an air- and a mixture compartment and normally substantially closing the passage therebetween, means for rotating said receptacle to gradually open said passage, and means 60 in the receptacle wall for simultaneously supplying fuel into said mixture compartment in amounts increasing with the size of said passage, and a valve member disposed in said mixture outlet and operatively connected with said receptacle to close said outlet when the receptacle is in normal position and to open it in accordance with the rotation of said receptacle, and means for varying the extent of said valve opening relatively to the angle of rotation of said receptacle in one direction, but for permitting the extent of valve opening to remain in proportion to said receptacle rotation when the latter is rotated in the other direction.
- 65 23. In a carbureter of the character described, the combination with an outer shell of substantially spherical shape having an air inlet in its lower hemisphere, and a mixture outlet in its upper hemisphere, a fuel receptacle pivotally disposed in said shell and dividing said shell into an air- and a mixture compartment, means for tilting said receptacle to establish an air passage between said two compartments, said receptacle having orifices in its wall adapted to supply fuel to the air current passing through said mixture compartment, when the receptacle is tilted into operative position in one direction, and a valve disposed on the upper side of said receptacle, and yieldingly seated against said mixture out-

- let in normal position of said receptacle, whereby said valve slides off its seat and opens said mixture outlet according to the degree to which said receptacle is tilted.
24. In a carbureter of the character described, the combination with an outer shell of substantially spherical shape having an air inlet in its lower hemisphere and a mixture outlet in its upper hemisphere, a fuel receptacle pivotally disposed in said shell and dividing said shell into an air- and a mixture compartment, means for tilting said receptacle to establish an air passage between said two compartments, said receptacle having orifices in its wall adapted to supply fuel to the air current passing through said mixture compartment, when the receptacle is tilted into operative position in one direction, and a valve disposed on the upper side of said receptacle, and yieldingly seated against said mixture outlet in normal position of said receptacle, whereby said valve slides off its seat and opens said mixture outlet according to the degree to which said receptacle is tilted, said valve having a cam on its upper face extending from the valve center radially thereon and of suitable height to bear against the valve seat to remove the valve from its seat the further, the greater the angle is through which said receptacle is tilted, to increase the size of the passage between said mixture compartment and said outlet, when the receptacle is tilted into operative position.
25. In a carbureter of the character described, the combination with an outer shell of substantially spherical shape having an air inlet in its lower hemisphere, and a mixture outlet in its upper hemisphere, a fuel receptacle pivotally disposed in said shell and dividing said shell into an air- and a mixture compartment, means for tilting said receptacle to establish an air passage between said two compartments, said receptacle having orifices in its wall adapted to supply fuel to the air current passing through said mixture compartment, when the receptacle is tilted into operative position in one direction, and a valve disposed on the upper side of said receptacle, and yieldingly seated against said mixture outlet in normal position of said receptacle, whereby said valve slides off its seat and opens said mixture outlet according to the degree to which said receptacle is tilted, said valve having a cam at its upper face extending radially thereon and of suitable height to bear against the valve seat to remove the valve from its seat the further the greater the angle is through which said receptacle is tilted, to increase the size of the passage between said mixture compartment and said outlet if the receptacle is tilted into operative position, said cam remaining inoperative when said receptacle is tilted in opposite direction and the valve slides off its seat to admit only air to said mixture outlet.
26. In a carbureter of the character described, the combination with an outer shell and a fuel receptacle disposed therein to rock on horizontal trunnions journaled in said shell and adapted when rocked to supply fuel into the space between the shell and the receptacle through orifices provided in its wall, said shell comprising an upper portion of substantially hemispherical shape with a mixture outlet at the top and of sufficient size to form a mixing chamber between its wall and the upper receptacle portion, the lower portion of said shell being formed of a cone shaped ring joining the upper shell with its upper rim and tapering away from it to increase the space between the receptacle and the ring wall toward its lower rim, said lower rim having a substantially hemispherical screen basket attached to it to admit air to the interior of the lower shell portion which air is permitted to pass into the mixing chamber past said orifices when said receptacle is tilted, and spring hasps for yieldingly joining said two shell portions.
27. In a carbureter of the character described, the combination of the rotatable fuel receptacle, means of supplying fuel thereto, a fuel supply valve, a float, a lever connected to said float, and a roller carried by said lever arranged adjacent to the valve but lateral to its axis.
28. In a carbureter of the character described, the combination with a shell having an air inlet and a mixture outlet, a fuel receptacle pivotally disposed in said shell and having its wall apertured to discharge fuel when the receptacle is rotated, and a screen pocket below the aperture of the receptacle to retain a priming charge.
29. In a carbureter of the character described, the combination with a shell having an air and mixture passage, of a rotatable fuel receptacle mounted thereon by trunnions, and spring controlled means for holding said trunnions to their seats.
30. A carbureter of the character described, having a shell provided with an air inlet and a mixture outlet, a removable and rotatable fuel receptacle mounted in said shell, having its wall apertured to discharge fuel into said shell, means for supplying fuel to the said receptacle, a valve for controlling said fuel supply automatically operating to stop the fuel supply when the fuel receptacle is removed.
31. A carbureter of the character described, having a fuel supply valve, a rotatable fuel receptacle, a float within said receptacle, a pivoted and rotatable lever connected to said float and having operative connection with said valve by means varying the extent of opening of the valve with

both the pivotal and rotatable changes of position of the lever.

32. In a carbureter of the character described, the combination of a shell having a carbureting chamber, a rotatable fuel receptacle and valve pivoted in said shell, apertured to discharge fuel, and approximately

closing the same below the carbureting chamber, the shell being flared or widened below said receptacle to free the air supply. 10
